(57) **CLAIM**

The ornamental design for a packaging box, as shown and described.

DESCRIPTION

FIG. 1 is a front perspective view showing the packaging box of the design;

FIG. 2 is a front view thereof;

FIG. 3 is a rear view thereof;

FIG. 4 is a left-side view thereof;

FIG. 5 is a right-side view thereof;

FIG. 6 is top view thereof;

FIG. 7 is bottom view thereof; and,

FIG. 8 is a top plan view showing the packaging box in an unfolded configuration.

The broken lines are shown for the purpose of illustrating parts of the article that form no part of the claimed design. The “Creating the Desired” logo shown in the drawings is a registered trademark of Yamada Manufacturing Co., Ltd.

1 Claim, 8 Drawing Sheets
